4 Claims. (Cl. 220—54)

This invention relates to improvements in sheet metal joints and methods of producing such joints.

In some applications, it is highly desirable to attach a member to a metal sheet of deformable material without interrupting the continuity of the metal sheet. One such application with which the present invention is particularly, but not exclusively, concerned is the attachment of a tab to a weakened portion or tear strip of a thin-walled metal sheet intended to form part of an airtight container such as, for example, containers for foodstuffs or beverages.

According to one aspect of the present invention, there is provided a method of joining a member to a metal sheet of deformable material which comprises the steps of deforming the metal sheet to form a first hollow boss without interrupting the continuity of the sheet, forming the member with a formation substantially complementary to the boss and dimensioned to extend into or around the boss, disposing one of the formation and the boss inside the other and adhesively uniting the boss and the formation.

According to another aspect of the present invention, there is provided a metal sheet of deformable material having a boss deformed out of the general plane of the sheet without interrupting the continuity thereof and a member having a formation dimensioned to extend into or around said boss and adhesively united therewith.

It is preferred to dimension the formation as a relatively close fit within the boss and it is desirable that the formation should be in the form of a further hollow boss which is closed at its end so as not to interrupt the continuity of the member.

The end of the further boss may, however, be open or apertured and, in some cases, the wall of the further boss may be discontinuous, i.e. split. In some cases, the wall of the further boss, whether continuous or discontinuous, may be serrated.

It is preferred that the member be of deformable metal sheet, the formation being deformed out of the general plane thereof by a pressing or stamping operation.

One embodiment of the invention will now be described by way of example as applied to a tab attached to a tear strip formed in the end of a thin-walled metal container, reference being made to the accompanying drawings in which:

FIG. 1 is a plan view of the top for the container showing the tear strip,

FIG. 2 is a view similar to FIG. 1 showing the tab attached,

FIG. 3 is an enlarged section taken on the line III—III of FIG. 2, and

FIG. 4 is a view similar to FIG. 2 of a modification.

In this example, the container end or lid 1 is formed from deformable sheet metal which may, for example, be an aluminium alloy and has a hollow boss 2 deformed out of the general plane thereof without interrupting the continuity of the end 1. The boss 2 is intended to extend inwardly of the container and may be of any convenient cross-section but, in this example, it is of circular cross-sec-

2

tion with the corners radiused to avoid sharp bends in the material.

The container end is formed with a pair of weakened line portions or score lines 3 to define a tear strip 4 in which the boss 2 is formed. The score lines 3 are joined at their one ends adjacent to the boss 2. Where the container is to contain liquids, the score lines 3 may extend for only a short distance as shown in FIG. 4, sufficient to allow the liquid to be poured, but, where the container is intended for solids, the score lines may extend substantially completely around the end of the container as shown in FIGS. 1 and 2, e.g. in the form of a spiral, to enable the major part of the container end to be opened.

A tab 5 is provided, also of deformable sheet metal, and is formed by a pressing or stamping operation with a hollow boss 6 dimensioned to be received as a relatively close fit within the boss 2. A measured quantity of adhesive is introduced into the boss 2 and the boss 6 is then inserted into the boss 2 so that the adhesive substantially fills the space between the bosses 2 and 6, the tab 5 extending in the general direction of continuity of the tear strip 4. The adhesive is then allowed or caused to set or cure to unite the tab 5 and tear strip 4. The adhesive, conveniently, is an epoxy-based unit adhesive such as that sold as Araldite AY 105 (Araldite being a registered trademark) and incorporates hardener HY 951 which is an aliphatic polyamine.

It will be appreciated that when the boss 6 is engaged in the boss 2 it is mechanically held against displacement in any direction other than in the direction normal to the general plane of the container end 1 and movement in this latter direction is prevented by the adhesive. When the container is sealed, it may be opened by lifting the free end of tab 5 and pulling it backwards over the bosses 2 and 6. This has the effect of causing the boss 6 to pivot in the clockwise direction as seen in FIG. 3 about the open end of the boss 2 at a location remote from the free end of the tab 5 and about an axis substantially parallel to the general plane of the container end 1 and substantially normal to the general direction of the tear strip 4 at the location of the boss 2. This causes the boss 6 to lean against and mechanically engage the wall of the boss 2 to lift the latter out of the general plane of the container end 1 thereby breaking the container end along the score lines 3 and releasing the tear strip 4. The major part of this operation is due to the lifting action produced by mechanical engagement of the boss 6 with the boss 2, the adhesive playing only a minor part.

The above described arrangement is preferred, but it will be understood that the boss 2 could be made to extend out of the container in which case it would be received as a close fit within a corresponding formed boss on the tab 5. It will also be understood the end of the boss 6 may be left open.

We claim:

1. A metal sheet of deformable material having a hollow boss deformed out of the general plane of the sheet without interrupting the continuity of the sheet, a member having a formation inserted into said hollow boss and dimensioned such that displacement of said formation in any direction other than normal to the general plane of said sheet is resisted by mechanical engagement between said boss and said formation and a chemical adhesive bond uniting said boss and said formation to prevent relative displacement in a direction normal to said general plane.

2. A metal sheet of deformable material having a first hollow boss deformed out of the general plane of the sheet without interrupting the continuity thereof, a pair of spaced weakened line portions in said sheet defining a tear strip containing said first hollow boss, a member having a second hollow boss received in said first boss as a relatively close fit so that displacement of said member about

an axis parallel to the general plane of the sheet and substantially normal to the direction of said tear strip at the location of said first boss produces mechanical engagement of said first and second bosses tending to lift said first boss and tear said weakened line portions and an adhesive bond uniting said first and second hollow bosses.

3. A metal container having an end wall with a first hollow boss deformed out of the general plane of said end wall without interrupting the continuity of said end wall, a pair of spaced weakened line portions formed in said end wall to embrace said first hollow boss and define a tear strip, a tab overlying said end wall and carrying a second hollow boss, one of said first and second hollow bosses extending as a relatively close fit into the other of said first and second bosses and said bosses being relatively dimensioned such that displacement of said tab about an axis parallel to the general plane of said end wall and substantially normal to the direction of said tear strip produces mechanical engagement of said first and second bosses tending to lift said first boss and tear said weakened line portions and an adhesive bond uniting said first and second hollow bosses.

4. A metal container having an end wall with a first

hollow boss deformed inwardly of said container out of the general plane of said end wall without interrupting the continuity of said end wall, a pair of spaced weakened line portions formed in said end wall to embrace said first hollow boss and define a tear strip, a tab overlying said end wall and carrying a second hollow boss extending as a relatively close fit into said first boss and dimensioned such that displacement of said tab about an axis parallel to the general plane of said end wall and substantially normal to the direction of said tear strip produces mechanical engagement of said first and second bosses tending to lift said first boss and tear said weakened line portions and an adhesive bond uniting said first and second hollow bosses.
